FOREIGN PATENT DOCUMENTS

EM 002735795-0001 * 7/2015

Primary Examiner — Michael A. Pratt

Assistant Examiner — Wendy L Arminio

(74) Attorney, Agent, or Firm — Knobbe, Martens, Olson
& Bear, LLP(57) **CLAIM**

The ornamental design for a cap, as shown and described.

DESCRIPTION

FIG. 1 is a top-front-left perspective view of a cap, showing my new design.

FIG. 2 is a front elevational view thereof.

FIG. 3 is a top plan view thereof.

FIG. 4 is a right side elevational view thereof. A left side elevational view is a mirror image of the right side elevational view.

FIG. 5 is a rear elevational view thereof.

FIG. 6 is a bottom plan view thereof; and,

FIG. 7 is a top-rear-right perspective view thereof, showing a lid portion of the cap in an open position.

The broken lines in the drawings depict environmental features that form no part of the claimed design.

1 Claim, 7 Drawing Sheets(56)
